IMAGE-CONVERTING DEVICE

George Stanley Percival Freeman, Chiswick, London, England, assignor to Cinema-Television Limited, London, England, a British company

Application June 15, 1950, Serial No. 168,231
In Great Britain June 29, 1949

9 Claims. (Cl. 315—10)

1

This invention relates to image-converting devices of the type, which may be utilized, for example, as television pick-up tubes or the like.

One of the difficulties encountered in television pick-up tubes of the image orthicon type is the loss of sensitivity caused by the mechanical blocking of photoelectrons originating in the image section of the tube by the capacitive grid or mesh of the storage electrode. Another disadvantage resides in the production of moiré patterns produced in the transmitted image as a result of beating between the scanning beam and the capacitive grid or mesh, unless the electrode potentials are very critically adjusted. Furthermore, the reproduced signal may be distorted at high light levels because of incomplete collection of secondary electrons released by the primary photoelectrons at the target; this leads to impaired picture fidelity, as indicated by the gamma of the device, and in light or dark halos surrounding dark or bright areas respectively in the image. Moreover, the signal multiplication by secondary emission at the target is comparatively poor.

It is a primary object of the present invention to provide a new and improved image-converting device which avoids one or more of the disadvantages of prior art devices.

It is a further object of the invention to provide a novel target electrode which is particularly adapted for use in an image-converting device of the double-ended type.

A further object of the invention is to provide an image-converting device which is capable of efficient operation on two different and distinct principles dependent upon the operating conditions, such as illumination and the like.

In accordance with the invention, a new and improved double-ended image-converting device comprises a storage electrode including a double-sided electron-impermeable target electrode, a thin imperforate layer of insulating material affixed to the target electrode, and a thin electron-permeable layer of conductive material affixed to the insulating layer. A pair of electron sources are respectively disposed on opposite sides of the storage electrode, and means are provided for projecting electrons from one of the sources through the conductive and insulating layers onto the target electrode to induce local transverse conduction currents in the insulating layer. Means are also provided for utilizing the conduction currents to effect image conversion.

In an image-converting device constructed in

2

accordance with the invention, the charge pattern stored on the target electrode may be either positive or negative. Moreover, the gain of the image section of the device may be controlled without materially affecting the focus of the photoelectrons incident on the storage electrode. As a still further feature, the device is adapted for use either with high-velocity scanning of the target as in the conventional image iconoscope, or with low-velocity scanning, as in the image orthicon. High-velocity scanning is advantageous under circumstances where high contrast and maximum picture resolution are desired, while low-velocity scanning permits a high light sensitivity to be attained.

The expression "double-sided target electrode" as used herein is intended to include any type of double-sided mosaic structure, as well as any type of thin uniform semi-conducting layer, of glass or the like, which exhibits the property of being transversely conductive while being substantially non-conductive in a lateral direction.

The features of the present invention which are believed to be novel are set forth with particularity in the appended claims. The invention, together with further objects and advantages thereof, may best be understood, however, by reference to the following description taken in connection with the accompanying drawing, in which:

Figures 1 and 2 are cross-sectional views, partly schematic, of image-converting devices constructed in accordance with the invention, and Figure 3 is a cross-sectional view of the storage electrode employed in the devices of Figures 1 and 2.

In the device of Figure 1, a substantially plane photo-cathode 10 is supported adjacent the inner surface of the end wall of an evacuated envelope 11, and an optical system 12, schematically represented by a single lens, is provided to focus an optical image on photo-cathode 10. Photoelectrons originating at cathode 10 are directed to a storage electrode 13 which comprises a double-sided target electrode 14, preferably constructed of a thin layer of semi-conducting glass, as for example silica fused with a large percentage of lead oxide, coated on the side facing photo-cathode 10 with a very thin imperforate layer 15 of insulating material such as silica or magnesium fluoride. A thin layer 16 of conductive material, such as aluminium or beryllium, is affixed to insulating layer 15. The conductive layer 16 is made sufficiently thick to be electrically con-

tive but thin enough to permit easy penetration by electrons originating at photo-cathode 10.

A second electron source, which may conveniently comprise a conventional scanning electron gun schematically represented at 17, is provided within envelope 11 on the side of storage electrode 13 opposite photo-cathode 10, and suitable magnetic-deflection coils 18 and 19 are provided to impart the desired scanning motion to the electron beam originating at electron gun 17. An elongated focussing coil 20 surrounds the entire envelope 11 to collimate the electrons originating respectively at photo-cathode 10 and electron gun 17.

The construction of electron gun 17 and photo-cathode 10 may assume any convenient form known to the art, and the storage electrode 13 may be supported in a conventional manner, as by means of a clamping ring (not shown) engaging the inner wall of envelope 11.

It is known in the art that if an insulator is penetrated and traversed by a fast moving stream of electrons, it is rendered locally conductive in a transverse direction with respect to the plane of the insulator (the direction of the electron beam) during the passage of the fast electrons. Moreover, by the application of suitable potentials to either surface of the insulator, a conduction current, of an order of magnitude larger than the penetrating current, may be caused to flow. In accordance with the present invention, the conduction current effect is utilized as follows:

Photoelectrons originating at cathode 10 are focussed onto the storage electrode 13 at high velocity and penetrate the conductive layer 16 and the insulating layer 15, coming to rest in the double-sided target electrode 14. The target electrode is stabilized at an equilibrium potential by means of the scanning beam from electron gun 17 which is deflected over the target 14 in accordance with a predetermined scanning pattern, as by means of deflection coils 18 and 19. A suitable potential, different from the equilibrium potential of the target electrode 14, is applied to the conductive layer 16 as by means of a lead-in conductor 21 which may also serve as an output terminal.

At the instant of passage of the primary photoelectrons from cathode 10 through the insulating layer 15, a large conduction current, proportional in intensity to the primary electron current, though perhaps ten times greater, flows from conductive layer 16 to target electrode 14, thus locally altering the potential of target electrode 14 and establishing a space-modulated charge pattern, corresponding to the light distribution from the optical image projected on photo-cathode 10, over the scanned surface of target electrode 14. Since the storage electrode structure does not contain a grid or mesh, the disadvantages of moiré patterns and mechanical blocking are not encountered. Moreover, since no secondary electrons are liberated, spurious shading signals are avoided.

It will be appreciated that the sign of the potential applied to conductive layer 16 with respect to the equilibrium potential of the target electrode 14 determines whether the space-modulated charge pattern stored on the target electrode is positive or negative with respect to the equilibrium potential which represents picture black. Small variations of the potential applied to conductive layer 16, which may, for example, be effected by means of a variable tap 22 coupled to lead-in conductor 21 and associated with a potentiometer

resistor 23 connected in parallel with a voltage source 24, afford a convenient control over the effective gain of the image section of the tube while having a negligible effect on the focus of the primary photoelectrons which travel at high velocities to penetrate the conductive and insulating layers 16 and 15 of the storage electrode 13. Thus, the light sensitivity of the tube, its contrast range, and its gamma characteristic may be brought under some degree of control to meet different conditions of operation.

In one mode of operation, the scanning beam from electron gun 17 may comprise scanning electrons of low velocity, as in the image orthicon. In this mode of operation, conductive layer 16 is biased in such a manner that the stored charges on target electrode 14 are positive in sign. Since the target electrode 14 is electron-impermeable, the scanning electrons are not collected by the conductive layer 16, and a suitable output load impedance, such as a resistor 25, may be connected to layer 16 by means of lead-in conductor 21 which then serves as an output terminal. The output signal so derived is more free from noise than that of an image orthicon wherein the return electron beam is incident on a collector mesh. If desired, the return electron beam may be used to derive the output signal in a manner well known in the art, and electron multiplication prior to the final output electrode may also be provided.

In another condition of operation, the scanning beam from electron gun 17 may comprise electrons of high velocity, as in the image iconoscope. With this mode of operation the sign of the stored charges may be made either positive or negative, and in either case, conductive layer 16 may constitute the output electrode. Moreover, if the stored charges are made positive with respect to picture black, the output signal may alternatively be derived from the return electron beam.

With either type of operation, the scanning beam from electron gun 17 also serves to restore the target electrode 14 to its equilibrium potential to condition the storage electrode 13 for storage and conversion of a succeeding image frame.

Thus, the embodiment of Figure 1 is adapted to operation with either high-velocity or low-velocity scanning, depending on the operating conditions encountered. Moiré patterns and mechanical blocking as well as spurious shading signals are avoided.

In the device of Figure 1, the writing beam from photo-cathode 19 is caused to penetrate the insulating layer 15 of the storage electrode 13, and the local transverse conduction currents induced in the thin insulating layer 15 are utilized to establish a charge pattern on the semi-conducting target electrode 14 which is space-modulated in accordance with the optical image to be converted. It is also possible, in accordance with the invention, to cause the reading beam to penetrate the thin insulating layer and thus to utilize the local conduction currents for the purpose of establishing an output current flow to the thin conducting layer of the storage electrode, thereby to produce an output signal representing the stored image. There is shown in Figure 2 an image-converting device of this latter type.

The device of Figure 2, with the exception of the storage electrode, is generally similar to the conventional image iconoscope; many parts of the device are similar to corresponding parts of the tube of Figure 1 and are designated by corre-

sponding primed reference numerals. The storage electrode 13' is identical to that of the tube of Figure 1 but is reversely oriented with respect to the photo-cathode 10' and the scanning electron gun 17'; that is, the semi-conducting target electrode 14' is directly exposed to photoelectron emission from cathode 10', while the reading electrons from scanning gun 17' are caused to penetrate the conductive layer 16' and the insulating layer 15' of the storage electrode 13' in order to reach the target electrode 14. A focusing solenoid 26 is concentrically arranged with respect to the envelope 11' around the image section of the tube to focus primary photoelectrons emitted from cathode 10', and a pair of anodes 27 and 28 are provided in the image section and the scanning section respectively for electrostatic focussing purposes; anodes 27 and 28 may conveniently assume the form of conductive coatings on the inner wall of the envelope 11'. As in the embodiment of Figure 1, magnetic-deflection coils 18' and 19' are provided to impart the desired scanning motion to the electron beam originating at electron gun 17', and an output terminal 21' is connected to the conductive layer 16' of the storage electrode 13'.

In operation, photoelectrons emitted from cathode 10', which are space-modulated in accordance with the optical image to be converted, are focussed and impinge upon the semi-conducting target electrode 14' at a velocity, for example, of the order of 1000 volts, and secondary electrons are liberated from the target surface which may be suitably treated to provide a high secondary emission ratio. Emission of secondary electrons from the target surface causes a positive charge to be transferred by leakage to the adjacent surface of the insulating layer 15', thereby to establish a charge pattern which is spaced-modulated to represent the optical image to be converted.

A high-velocity scanning beam from electron gun 17' is directed over the surface of conductive layer 16' in accordance with a predetermined scanning pattern, and this reading beam penetrates both the conductive layer 16' and the insulating layer 15' to render the latter conductive in a transverse direction. As a result, the positive charge established on the insulator surface leaks through the insulating layer 15' to the conductive layer 16', by virtue of the local transverse conduction currents which are established in the insulator when it is traversed by an electron beam. A suitable potential different from the equilibrium potential of the target electrode 14' is applied to the conductive layer 16' by way of lead-in conductor 21', and at the instant of passage of the scanning electrons through an elementary area of the insulating layer 15', a large conduction current proportional in intensity to the primary current from the corresponding elementary area of the photo-cathode 10', though perhaps ten times greater, flows to the conductive layer 16'. By providing a suitable load impedance (not shown) in the circuit between conductive layer 16' and electron gun 17', an electrical output signal which is modulated in accordance with the optical image to be transmitted may be produced, and lead-in conductor 21' may furnish a convenient output terminal from which the output signal may be derived.

The arrangement of Figure 2 possesses all the inherent advantages of the image iconoscope while avoiding its major disadvantages, namely, that the scanning electrons from the reading gun

may penetrate the storage electrode and cause spurious signals by virtue of their subsequent interference with the operation of the image section of the tube. In the device of Figure 2, the semi-conducting target electrode 14' is electron-impermeable so that the scanning electrons cannot penetrate the storage electrode and spurious signals are avoided. Moreover, the storage electrode is simple of construction and no substantial redistribution of electrons from the scanning beam is possible, so that shading signals are also avoided.

The construction of storage electrode 13 of the device of Figure 1 and storage electrode 13' of the device of Figure 2 is illustrated in cross-section in Figure 3.

It is also possible, in accordance with the invention, to utilize the storage electrode in certain other environments to meet different conditions of operation. For example, the storage electrode may be particularly useful in an image-converting device of the image-storage or memory tube type. Such a device may advantageously be provided in the form of a uniaxial structure having reading and writing electron guns on opposite sides of a storage electrode which per se is constructed as illustrated in Figures 1 and 2. As in the other embodiments of the invention, local transverse conduction currents induced in the insulating layer are utilized to provide image storage and conversion.

In all of its applications, the storage electrode provided by the invention, comprising a target electrode to which is affixed a thin insulating layer, and a thin conductive layer affixed to the insulating layer, affords numerous advantages over storage electrodes previously used in conventional image-converting devices. Having no mesh or grid, the storage electrode of the present invention places no limitation on obtainable picture resolution. Moreover, since the target electrode portion of the storage electrode is electron-impermeable, electrons from the scanning section of the tube are precluded from adversely affecting operation of the image section, and vice versa.

While particular embodiments of the present invention have been shown and described, it is apparent that various changes and modifications may be made, and it is therefore contemplated in the appended claims to cover all such changes and modifications as fall within the true spirit and scope of the invention.

I claim:

1. A double-ended image-converting device comprising: a storage electrode including a double-sided electron-impermeable target electrode, a thin imperforate layer of insulating material affixed to said target electrode, and a thin electron-permeable layer of conductive material affixed to said insulating layer; a pair of electron sources respectively disposed on opposite sides of said storage electrode; means for projecting electrons from one of said sources through said layers onto said target electrode to induce local transverse conduction currents in said insulating layer; and means utilizing said conduction currents to effect image conversion.

2. A double-ended image-converting device comprising: a storage electrode including a double-sided electron-impermeable target electrode, a thin imperforate layer of insulating material affixed to said target electrode, and a thin electron-permeable layer of conductive material affixed to said insulating layer; a pair of electron

sources respectively disposed on opposite sides of said storage electrode; means for projecting electrons from one of said sources through said layers onto said target electrode to induce local transverse conduction currents in said insulating layer; and means, including means for projecting electrons from the other of said sources onto said target electrode, for utilizing said conduction currents to effect image conversion.

3. A double-ended image-converting device comprising: a storage electrode including a double-sided electron-impermeable target electrode, a thin imperforate layer of insulating material affixed to said target electrode, and a thin electron-permeable layer of conductive material affixed to said insulating layer; a pair of electron sources respectively disposed on opposite sides of said storage electrode; means for projecting electrons from one of said sources through said layers onto said target electrode to induce local transverse conduction currents in said insulating layer; and means including an output terminal connected to said conductive layer for application of an energizing potential thereto to utilize said conduction currents to effect image conversion.

4. A double-ended image-converting device comprising: a storage electrode including a double-sided electron-impermeable target electrode, a thin imperforate layer of insulating material affixed to said target electrode, and a thin electron-permeable layer of conductive material affixed to said insulating layer; a pair of electron sources respectively disposed on opposite sides of said storage electrode; means for modulating electrons from a first one of said sources in accordance with an optical image; means for projecting said modulated electrons from said first source through said layers onto said target electrode to induce local transverse conduction currents in said insulating layer thereby to establish a space-modulated charge pattern on said target electrode representing said optical image; and means, including means for projecting electrons from the other of said sources onto said target electrode, for converting said space-modulated charge pattern to an electrical signal.

5. A double-ended image-converting device comprising: a storage electrode including a double-sided electron-impermeable target electrode, a thin imperforate layer of insulating material affixed to said target electrode, and a thin electron-permeable layer of conductive material affixed to said insulating layer; a pair of electron sources respectively disposed on opposite sides of said storage electrode; means for modulating electrons from a first one of said sources in accordance with an optical image; means for projecting said modulated electrons from said first source onto said target electrode to establish a space-modulated charge pattern thereon representing said optical image; means for projecting

electrons from the other of said sources through said layers onto said target electrode to induce local transverse conduction currents in said insulating layer in accordance with said space-modulated charge pattern; and means including an output terminal connected to said conductive layer for utilizing said conduction currents to effect conversion of said optical image to an electrical signal.

6. A double-ended image converting device comprising: a storage electrode including a double-sided electron-impermeable target electrode, a thin imperforate layer of insulating material affixed to said target electrode, and a thin electron-permeable layer of conductive material affixed to said insulating layer; a pair of electron sources respectively disposed on opposite sides of said storage electrode; means, including means for modulating electrons from a first one of said sources in accordance with an optical image, for storing a charge replica of said image on said storage electrode; means for projecting electrons from one of said sources through said layers onto said target electrode to induce local transverse conduction currents in said insulating layer; means including an output terminal connected to said conductive layer for application of an energizing potential thereto to utilize said conduction currents to effect image conversion; and means for varying said energizing potential to control the gain of said image-storing means.

7. A storage electrode for an image-converting device comprising: a double-sided semi-conducting glass electron-impermeable target electrode; a thin imperforate layer of insulating material affixed to said target electrode; and a thin electron-permeable layer of conductive material affixed to said insulating layer.

8. A storage electrode for an image-converting device comprising: a double-sided electron-impermeable target electrode; a thin imperforate layer of silica affixed to said target electrode; and a thin electron-permeable layer of conductive material affixed to said silica layer.

9. A storage electrode for an image-converting device comprising: a double-sided electron-impermeable target electrode; a thin imperforate layer of magnesium fluoride affixed to said target electrode; and a thin electron-permeable layer of conductive material affixed to said first-mentioned layer.
